UNITED STATES PATENT OFFICE.

CHARLES M. TATOSIAN, OF NEWARK, NEW JERSEY.

PROPELLED MECHANISM FOR VEHICLES.

1,290,682.

Specification of Letters Patent.

Patented Jan. 7, 1919.

Application filed August 2, 1918. Serial No. 247,959.

To all whom it may concern:

Be it known that I, CHARLES M. TATOSIAN, a subject of the King of Armenia, residing at Newark, in the county of Essex and State 5 of New Jersey, have invented certain new and useful Improvements in Propelling Mechanism for Vehicles; and I do hereby declare the following to be a full, clear, and exact description of the invention, such as 10 will enable others skilled in the art to which it appertains to make and use the same, reference being had to the accompanying drawings, and to characters of reference marked thereon, which form a part of this 15 specification.

This invention relates, generally, to improvements in propelling mechanisms of the character employed in connection with manually propelled vehicles, such as velocipedes, bicycles, and the like; and, the present invention has reference, more particularly, to a novel propelling mechanism in which sprocket-gear and chain mechanism are operated by the reciprocatory actions, 25 alternately, of a pair of pedals, instead of the complete circular motion of such pedals.

The present invention, therefore, has for its principal object to provide a propelling mechanism of the general character herein- 30 after more fully set forth, which is simple in its construction, is efficient in its operation, and is productive in producing greater power, than by means of the usual forms of propelling mechanism now ordinarily in use.

The invention has for its further object to provide in connection with the construction of propelling mechanism, means adapted to be actuated by the operator, whereby the mechanism acts to produce a "slack" of the 35 chain, so that the mechanism can also be used in the manner of the usual "coaster-brake".

Other objects of this invention not at this time more particularly enumerated will be 40 clearly understood from the following detailed description of the same.

With the various objects of the present invention in view, the said invention consists, primarily, in the novel propelling 45 mechanism for vehicles, such as velocipedes, bicycles, and the like, hereinafter more fully set forth; and, the present invention consists, furthermore, in the several arrangements and combinations of the several de- 50 vices and parts, as well as in the details of

the construction of the said parts, all of which will be more fully described in the following specification, and then finally embodied in the clauses of the claim which are appended to and which form an essential 60 part of the said specification.

The present invention is clearly illustrated in the accompanying drawings, in which:—

Figure 1 is a side elevation of the said propelling mechanism, as applied to the 65 frame of a bicycle, portions of the said frame being also shown in side elevation in said view; and Fig. 2 is a top or plan view of said propelling mechanism, the main hub and frame portion of the vehicle, in said 70 view being represented in section.

Fig. 3 is a central longitudinal vertical section of the mechanism, said section being taken on line 3—3 in said Fig. 2, and said view being made on an enlarged scale. 75

Fig. 4 is a transverse vertical section taken on line 4—4 in said Fig. 3; Fig. 5 is a similar section taken on line 5—5 in said Fig. 3; and Fig. 6, likewise, is a transverse vertical 80 section, taken on line 6—6 in said Fig. 3. 80

Similar characters of reference are employed in all of the several figures of the drawings, to indicate corresponding parts.

Referring now to the several figures of the drawings, the reference-characters 1, 2 85 and 3 indicate fragmentary portions of the usual reaches of a bicycle-frame, the said reaches being secured, in any usual manner, to the usual tubular-bearing hub 4, closed by the respective end-plates 5 and 6 which 90 are respectively formed with the bearing- portions 7.

The reference-character 8 indicates a main shaft or spindle of suitable length, the said shaft or spindle being centrally perforated, 95 as at 9, and having mounted in said perforation a laterally extending pin 10, upon the free end-portions of which are rotatably mounted a pair of bevel-gears 11 and 12, said gears being maintained in position 100 upon the ends of said pin by means of heads or enlargements 13 and a pair of sleeves 14, as shown in Figs. 3 and 4 of the drawings.

In mesh with the said bevel-gears 11 and 12 are a pair of bevel-gears 15 and 16, said 105 last-mentioned gears having their hubs loosely and rotatably mounted upon said shaft or spindle 8, on opposite sides of the said pin 10. Operatively secured upon the hub of the bevel-gear 15, by means of a screw 110

- 17, or other suitable fastening means, is an annular sleeve-like member or element 18, which extends from the inner side or face of a hub 19, said hub being also mounted 5 upon a portion of said shaft or spindle 8, and having extending therefrom at the proper angle a crank-arm or pedal 20 carrying upon its free end a foot-treadle, as 21. In a similar manner, there is secured upon 10 the hub 16, by means of a screw 22, the annular sleeve-like member or element 23, which extends from the inner side or face of a hub 24, said hub being also mounted upon a portion of said shaft or spindle 8, and having extending therefrom at a proper angle 15 a crank-arm or pedal 25 carrying upon its free end a foot-treadle, as 26. As shown more particularly in Fig. 2 of the drawings, the hub 19 is also provided upon its inner side or face and concentric with said sleeve-like member or element 18 with an annular arrangement of ratchet-teeth 27, and the hub 24 is also provided upon its inner side or face and concentric with the 20 sleeve-like member or element 23 with an annular arrangement of ratchet-teeth 28, the direction of the teeth 27 being opposed to the direction of the teeth 28. The positions of the above-mentioned pedal-carrying hubs 25 30 19 and 24 are mounted against movement upon the shaft or spindle 8 longitudinally with relation to said shaft or spindle, by an arrangement of washers 29 and 30 and nuts 31 and 32 screwed upon the respective screw-threaded end-portions 33 of the said shaft or spindle, and by means of the previously mentioned bevel-gears, as will be clearly understood from an inspection of said Fig. 3 of the drawings.
- 40 As shown, an arrangement of anti-friction rollers 34 and 35 is also disposed between said shaft or spindle 8, and the inner surface-portions of the respective sleeve-like elements 18 and 23, other anti-friction rollers 36 and 37 being disposed about the outer surface-portions of the respective sleeve-like elements 18 and 23.
- 50 Slidably disposed upon the said rollers 36, so as to move in the direction of the arrow x , see Fig. 3, is a sleeve-like member or element, as 38, said sleeve being formed at its one end with an annular off-set, as 39, against which is fitted and secured by means of screws 40, or other suitable fastening 55 means, a sprocket-wheel 41, for conveying motion to the usual sprocket or link-chain 42. Extending from the outer face of the said off-set member 39 is an annular arrangement of ratchet-teeth 43 normally in engagement with the ratchet-teeth 27 of the pedal-carrying hub 19.
- 60 Upon its opposite end-portion, the said sleeve-like member or element 38 is formed with longitudinally extending segmental figures, as 44, and spaces 45, alternately dis-

posed as represented in Fig. 4 of the drawings, and for the purposes to be presently more fully set forth.

Similarly, slidably disposed upon the rollers 37, so as to move in the direction of the arrow y , in said Fig. 3, is another sleeve-like member or element, as 47, provided upon its outer face with an annular arrangement of ratchet-teeth 48 normally in engagement with the ratchet-teeth 28 of the pedal-carrying hub 24. The said member or element 47 is likewise provided with longitudinally extending segmental fingers, as 49, which extend into and are slidably disposed in the above-mentioned space 45 between the fingers 44, suitable spaces 50, see Fig. 2 of the drawings, being also provided between the fingers 49 into which extend and are slidably disposed the previously mentioned fingers 44, so that the two members 85 or elements 38 and 47, with their alternately disposed and slidably engaged fingers, will provide a clutch-device for the purposes hereinafter more fully set forth.

Suitably mounted upon the said fingers 90 49 and surrounding the same, is a stop-ring 51 formed with projecting portions, as 52 which extend into and register with the spaces 50 between said fingers 49, as shown in Fig. 5 of the drawings; and, mounted 95 upon the fingers 44 of the member or element 38 is another stop-ring, as 53, also provided with projecting portions, similar to the projecting portions, 52, but not here shown, and which extend into and register with the 100 spaces 45 between the fingers 44. A coil-spring 54 is located between the two rings 51 and 53 to spread the two members of the clutch-device, under normal initial conditions in directions opposite from those indicated by the arrows x and y , to thereby 105 normally cause the engaging relation of the ratchet-teeth 27 and 43, and of the ratchet-teeth 28 and 48, as will be evident.

Anti-friction rollers 54 surround portions of the said sleeve-like member or element 47 and its fingers 49, between the longitudinal-hub 4, and the end-wall 5 and stop-ring 51, other anti-friction rollers 55 being arranged about portions of the sleeve-like member or element 38 and its fingers 44, 115 between the bearing-hub 4, and the end-wall 6 and stop-ring 53.

The operation of the mechanism hereinabove described will be self-evident from the 120 foregoing description of the same, and from an inspection of the several figures of the drawings, and it suffices merely to say, that when the operator presses the pedal 25 in a downward direction, in the direction of the 125 arrow x , in Fig. 1, the other pedal 20 will automatically move in an opposite and upward direction, in the direction of the arrow y ; and, vice versa, when the pedal 20 is moved downwardly, the pedal 25 moves 130

automatically in an upward direction, owing to the alternating active engagement of the one set of ratchet-teeth and non-active sliding engagement of the other set of ratchet-teeth. Thus, the alternating reciprocatory movements of the respective pedals, and the respective movements of the co-acting parts of the mechanism will produce a continuous rotary movement of the sprocket-wheel 41 at 10 all times in one and the same direction, the shaft or spindle 8 at all times maintaining a fixed non-rotative relation.

In order to "brake" the vehicle, by what is termed "back-pedaling" I have secured upon 15 the screw-threaded portions 33 of the shaft or spindle 8, by means of washers 56 and lock-nuts 57, a pair of rods 58, which are connected by means of a cross-bar rod 59, locked to said rods 58 by means of lock-nuts 20 60 and 61, and provided with foot-actuated means, as 62. The mechanical assemblage of the several devices and parts, in such case, is such, that a downward pressure upon either or both of said actuating means 62 25 produces a slight movement of the shaft or spindle 8 in a reverse direction, against the momentum in the forward direction, thereby, by means of the chain, causing a drag upon the tire of the rear wheel of the vehicle, to suddenly stop or "brake" the vehicle.

To limit and arrest the downward movements of the respective pedals at the proper times, and to provide for the proper working of the mechanism, the said rods 58 are 30 provided with downwardly extending members, as 63, from which extend laterally suitable pins or studs 64, preferably provided with cushioning devices 65 of rubber, or the 35 like, and with which the said pedals are respectively brought at the ends of their downward strokes into arrested engagement, as will be clearly evident from an inspection of Figs. 1 and 3 of the drawings.

45 From the foregoing description, it will be clearly evident that I have produced a simply constructed and efficiently operating propelling mechanism, and one, while it is operated with but slight exertion on the part 50 of the operator, produces an increased power in operating the vehicle.

I am fully aware, that some changes may be made in the general arrangements and combinations of the various devices and 55 parts, as well as in the details of the construction of the said parts, without departing from the scope of the said specification and the claims appended thereto. Hence, I do not limit my present invention as set 60 forth in the said specification, nor do I confine myself to the exact details of the construction of the said parts, as illustrated in the accompanying drawings.

I claim:—

65 1. A propelling mechanism for vehicles

comprising, a main shaft, crank-pedals mounted upon said shaft, said crank-pedals being capable of reciprocatory motion, a clutch-mechanism also mounted upon said shaft, adapted to be actuated by the alternate downward movements of said crank-pedals, and a sprocket-wheel mounted with 70 said clutch-mechanism and adapted to receive a continuous rotary movement from said actuated clutch-mechanism, combined 75 with means connected and coöperating with said shaft to produce "back-pedaling," consisting of rearwardly extending rods fixed to said shaft, a connecting bar between said rods, and foot-actuated means connected 80 with said connecting bar.

2. A propelling mechanism for vehicles comprising, a main shaft, crank-pedals mounted upon said shaft, said crank-pedals being capable of reciprocatory motion, a 85 clutch-mechanism also mounted upon said shaft, adapted to be actuated by the alternate downward movements of said crank-pedals, and a sprocket - wheel mounted with said clutch-mechanism and adapted to receive a 90 continuous rotary movement from said actuated clutch-mechanism, combined with means connected and coöperating with said shaft to produce "back-pedaling", consisting 95 of rearwardly extending rods fixed to said shaft, a connecting bar between said rods, and foot-actuated means connected with said connecting bar, and means connected with said rearwardly extending rods for limiting and arresting the downward movements of 100 said crank-pedals.

3. A propelling mechanism for vehicles comprising, a main shaft, crank-pedals mounted upon said shaft, said crank-pedals being capable of reciprocatory motion, a 105 clutch-mechanism also mounted upon said shaft, adapted to be actuated by the alternate downward movements of said crank-pedals, and a sprocket-wheel mounted with said clutch-mechanism and adapted to receive a continuous rotary movement from said actuated clutch-mechanism, combined with means connected and coöperating with said shaft to produce "back-pedaling", consisting 110 of rearwardly extending rods fixed to said shaft, a connecting bar between said rods, and foot-actuated means connected with said connecting bar, and means connected with said rearwardly extending rods for limiting and arresting the downward movements of 115 said crank-pedals, consisting of members extending downwardly from said rearwardly extending rods, and stop-pins extending laterally from said members with which said crank-pedals are 120 adapted to be brought into engagement.

4. A propelling mechanism for vehicles comprising, a main shaft, crank-pedals mounted upon said shaft, said crank-pedals being capable of reciprocatory motion, a 125

set of intermeshing bevel-gears mounted upon said shaft, gear-actuating means extending from said crank-pedals respectively connected with some of said gears for actuating said gear-mechanism, slidably-disposed clutch-members mounted upon the gear-actuating means of each crank-pedal, a sprocket-wheel connected with and mounted upon the clutch member of one of said 5 crank-pedals, and a means of slidable connection between each clutch-member and the hub of each crank-pedal, all arranged so that the reciprocatory motions of said crank-pedals will produce a continuous rotary 10 motion of said sprocket-wheel.

5. A propelling mechanism for vehicles comprising, a main shaft, crank-pedals mounted upon said shaft, said crank-pedals being capable of reciprocatory motion, a 20 set of intermeshing bevel-gears mounted upon said shaft, gear-actuating means extending from said crank-pedals respectively connected with some of said gears for actuating said gear-mechanism, slidably disposed 25 clutch-members mounted upon the gear-actuating means of each crank-pedal, a sprocket-wheel connected with and mounted upon the clutch member of one of said crank-pedals, and a means of slidable connection 30 between each clutch-member and the hub of each crank-pedal, all arranged so that the reciprocatory motions of said crank-pedals will produce a continuous rotary motion of said sprocket-wheel, combined with means for limiting and arresting 35 the downward movement of said crank-pedals.

6. A propelling mechanism for vehicles comprising, a main shaft, crank-pedals 40 mounted upon said shaft, said crank-pedals being capable of reciprocatory motion, a set of intermeshing bevel-gears mounted upon said shaft, gear-actuating means extending from said crank-pedals respectively connected with some of said gears for actuating 45 said gear-mechanism, slidably disposed clutch-members mounted upon the gear-actuating means of each crank-pedal, a sprocket-wheel connected with and mounted upon the clutch member of one of said crank-pedals, and a means of slidable connection 50 between said clutch-member and the hub of each crank-pedal, all arranged so that the reciprocatory motions of said crank-pedals will produce a continuous rotary motion of said sprocket-wheel, combined with means for limiting and arresting the downward movement of said crank-pedals, consisting of devices fixed upon said shaft, and 55 stop-pins extending laterally from said devices with which the said crank-pedals are adapted to be brought into engagement.

7. A propelling mechanism for vehicles comprising, a main shaft, crank-pedals 60 mounted upon said shaft, said crank-pedals 65

being capable of reciprocatory motion, a set of intermeshing bevel-gears mounted upon said shaft, gear-actuating means extending from said crank-pedals respectively connected with some of said gears for actuating said gear-mechanism, slidably-disposed clutch-members mounted upon the gear-actuating means of each crank-pedal, a sprocket-wheel connected with and mounted upon the clutch member of one of said crank-pedals, and a means of slidable connection between each clutch-member and the hub of each crank-pedal, all arranged so that the reciprocatory motions of said crank-pedals will produce a continuous rotary motion of said sprocket-wheel, combined with means connected with and extending rearwardly from said shaft to produce "back-pedaling".

8. A propelling mechanism for vehicles comprising, a main shaft, crank-pedals mounted upon said shaft, said crank-pedals being capable of reciprocatory motion, a set of intermeshing bevel-gears mounted upon said shaft, gear-actuating means extending from said crank-pedals respectively connected with some of said gears for actuating said gear-mechanism, slidably disposed clutch members mounted upon the gear-actuating means of each crank-pedal, a sprocket-wheel connected with and mounted upon the clutch member of one of said crank-pedals, and a means of slidable connection between each clutch-member and the hub of each crank-pedal, all arranged so that the reciprocatory motions of said crank-pedals will produce a continuous rotary motion of said sprocket-wheel, combined with means connected with and extending rearwardly from said shaft to produce "back-pedaling".

9. A propelling mechanism for vehicles comprising, a main shaft, crank-pedals mounted upon said shaft, said crank-pedals being capable of reciprocatory motion, a set of intermeshing bevel-gears mounted upon said shaft, gear-actuating means extending from said crank-pedals respectively connected with some of said gears for actuating said gear-mechanism, slidably disposed clutch -members mounted upon the gear-actuating means of each crank -pedal, a sprocket-wheel connected with and mounted upon the clutch member of one of said crank-pedals, and a means of slidable connection between each clutch-member and the hub of each crank-pedal, all arranged so that the reciprocatory motions of said crank-pedals will produce a continuous rotary motion of said sprocket-wheel, combined with means connected with and coöperating with said shaft to produce "back-pedaling", consisting of rearwardly extending rods fixed to said shaft, a connecting bar between said rods, and foot-actuated means connected with said connecting bar.

10. A propelling mechanism for vehicles comprising, a main shaft, crank-pedals mounted upon said shaft, said crank-pedals being capable of reciprocatory motion, a set of intermeshing bevel-gears mounted upon said shaft, gear-actuating means extending from said crank-pedals respectively connected with some of said gears for actuating said gear-mechanism, slidably disposed clutch-members mounted upon the gear-actuating means of each crank-pedal, a sprocket-wheel connected with and mounted upon the clutch member of one of said crank-pedals, and a means of slidable connection between each clutch-member and the hub of each crank-pedal, all arranged so that the reciprocatory motions of said crank-pedals will produce a continuous rotary motion of said sprocket-wheel, combined with means connected with and coöperating with said shaft to produce "back-pedaling", consisting

of rearwardly extending rods fixed to said shaft, a connecting bar between said rods, and foot-actuated means connected with said connecting bar, and means connected with 5 said rearwardly extending rods for limiting and arresting the downward movements of said crank-pedals.

10. A propelling mechanism for vehicles comprising, a main shaft, crank-pedals mounted upon said shaft, said crank-pedals being capable of reciprocatory motion, a set of intermeshing bevel-gears mounted upon said shaft, gear-actuating means extending from said crank-pedals respectively connected with some of said gears for actuating 15 said gear-mechanism, slidably disposed clutch-members mounted upon the gear-actuating means of each crank-pedal, a sprocket-wheel connected with and mounted 20 upon the clutch member of one of said crank-pedals, and a means of slidable connection between each clutch-member and the hub of each crank-pedal, all arranged so that the reciprocatory motions of said 25 crank-pedals will produce a continuous rotary motion of said sprocket-wheel, combined with means connected and co-operating with said shaft to produce "back-pedaling", consisting of rearwardly extending 30 rods fixed to said shaft, a connecting bar between said rods, and foot-actuated means connected with said connecting bar, and means connected with said rearwardly extending rods for limiting and arresting the 35 downward movements of said crank-pedals, consisting of members extending downwardly from said rearwardly extending rods, and stop-pins extending laterally from said members with which said crank-pedals 40 are adapted to be brought into engagement.

11. A propelling mechanism for vehicles comprising, a main shaft, crank-pedals mounted upon said shaft, said crank-pedals being capable of reciprocatory motion, a set 45 of intermeshing bevel-gears mounted upon said shaft, annular sleeve-like members extending inwardly from the hubs of said crank-pedals, means for securing said members to some of said gears for actuating said 50 gear-mechanism, slidably disposed and spring-controlled clutch-members mounted upon the respective sleeve-like members of said crank-pedals, a sprocket-wheel connected with and mounted upon the clutch-member of one of said crank-pedals, and 55 ratchet-teeth extending from each clutch-member and the hub of each crank-pedal, the ratchet-teeth of each clutch-member being in slid- 60 able engagement with the ratchet-teeth of a respective crank-pedal, all arranged so that the reciprocatory motion of said crank-pedals will produce a continuous rotary motion of said sprocket-wheel, combined with means for limiting and arresting the downward movements of said crank-pedals, consisting of devices fixed upon said shaft, and stop-pins extending laterally from said devices with which the said crank-pedals are 65 adapted to be brought into engagement.

12. A propelling mechanism for vehicles comprising, a main shaft, crank-pedals 65

mounted upon said shaft, said crank-pedals being capable of reciprocatory motion, a set of intermeshing bevel-gears mounted upon said shaft, annular sleeve-like members extending inwardly from the hubs of said crank-pedals, means for securing said members to some of said gears for actuating said gear-mechanism, slidably disposed and spring-controlled clutch-members mounted upon the respective sleeve-like members of 70 said crank-pedals, a sprocket-wheel connected with and mounted upon the clutch-member of one of said crank-pedals, and ratchet-teeth extending from each clutch-member and the hub of each crank-pedal, the ratchet-teeth of each clutch-member being in slid- 75 able engagement with the ratchet-teeth of a respective crank-pedal, all arranged so that the reciprocatory motion of said crank-pedals will produce a continuous rotary motion of said sprocket-wheel, combined with means for limiting and arresting the downward movements of said crank-pedals.

13. A propelling mechanism for vehicles comprising, a main shaft, crank-pedals 90 mounted upon said shaft, said crank-pedals being capable of reciprocatory motion, a set of intermeshing bevel-gears mounted upon said shaft, annular sleeve-like members extending inwardly from the hubs of 95 said crank-pedals, means for securing said members to some of said gears for actuating said gear-mechanism, slidably disposed and spring-controlled clutch-members mounted upon the respective sleeve-like members of 100 said crank-pedals, a sprocket-wheel connected with and mounted upon the clutch-member of one of said crank-pedals, and ratchet-teeth extending from each clutch-member and the hub of each crank-pedal, the ratchet-teeth of each clutch-member being in slid- 105 able engagement with the ratchet-teeth of a respective crank-pedal, all arranged so that the reciprocatory motion of said crank-pedals will produce a continuous rotary motion of said sprocket-wheel, combined with means for limiting and arresting the downward movements of said crank-pedals, consisting of devices fixed upon said shaft, and stop-pins extending laterally from said devices with which the said crank-pedals are 110 adapted to be brought into engagement.

14. A propelling mechanism for vehicles comprising, a main shaft, crank-pedals mounted upon said shaft, said crank-pedals being capable of reciprocatory motion, a set of intermeshing bevel-gears mounted upon said shaft, annular sleeve-like members extending inwardly from the hubs of said crank-pedals, means for securing said members to some of said gears for actuating said gear-mechanism, slidably disposed and spring-controlled clutch-members mounted upon the respective sleeve-like members of 120 said crank-pedals, a sprocket-wheel con- 125

nected with and mounted upon the clutch-member of one of said crank-pedals, and ratchet-teeth extending from each clutch-member and the hub of each crank-pedal, 5 the ratchet-teeth of each clutch-member being in slidible engagement with the ratchet-teeth of a respective crank-pedal, all arranged so that the reciprocatory motion of said crank-pedals will produce a continuous 10 rotary motion of said sprocket-wheel, combined with means connected with and extending downwardly from said shaft to produce "back-pedaling".

15. A propelling mechanism for vehicles comprising, a main shaft, crank-pedals mounted upon said shaft, said crank-pedals being capable of reciprocatory motion, a set of intermeshing bevel-gears mounted upon said shaft, annular sleeve-like members extending inwardly from the hubs of said crank-pedals, means for securing said members to some of said gears for actuating said gear-mechanism, slidably disposed and spring-controlled clutch-members mounted 20 upon the respective sleeve-like members of said crank-pedals, a sprocket-wheel connected with and mounted upon the clutch-member of one of said crank-pedals, and ratchet-teeth extending from each clutch-member 25 and the hub of each crank-pedal, the ratchet-teeth of each clutch-member being in slidible engagement with the ratchet-teeth of a respective crank-pedal, all arranged so that the reciprocatory motion of said crank-pedals will produce a continuous rotary motion 30 of said sprocket-wheel, combined with means connected and coöperating with said shaft to produce "back-pedaling", consisting of rearwardly extending rods fixed to 35 said shaft, a connecting bar between said rods, and foot-actuated means connected with said connecting bar.

16. A propelling mechanism for vehicles comprising, a main shaft, crank-pedals mounted upon said shaft, said crank-pedals being capable of reciprocatory motion, a set of intermeshing bevel-gears mounted upon said shaft, annular sleeve-like members extending inwardly from the hubs of said crank-pedals, means for securing said members to some of said gears for actuating said gear-mechanism, slidably disposed and spring-controlled clutch-members mounted 50 upon the respective sleeve-like members of said crank-pedals, a sprocket-wheel connected with and mounted upon the clutch-member of one of said crank-pedals, and ratchet-teeth extending from each clutch-member 55 and the hub of each crank-pedal, the ratchet-

teeth of each clutch-member being in slidible engagement with the ratchet-teeth of a respective crank-pedal, all arranged so that the reciprocatory motion of said crank-pedals will produce a continuous rotary motion of said sprocket-wheel, combined with means connected and coöperating with said shaft to produce "back-pedaling," consisting of rearwardly extending rods fixed to said shaft, a connecting bar between said rods, and foot-actuated means connected with said connecting bar, and means connected with said rearwardly extending rods for limiting and arresting the downward movements of said crank-pedals.

17. A propelling mechanism for vehicles comprising, a main shaft, crank-pedals mounted upon said shaft, said crank-pedals being capable of reciprocatory motion, a set of intermeshing bevel-gears mounted with relation to said shaft, annular sleeve-like members extending inwardly from the hubs of said crank-pedals, means for securing said members to some of said gears for actuating said gear-mechanism, slidably disposed and spring-controlled clutch-members mounted 80 upon the respective sleeve-like members of said crank-pedals, a sprocket-wheel connected with and mounted upon the clutch-member of one of said crank-pedals, and ratchet-teeth extending from each clutch-member 85 and the hub of each crank-pedal, the ratchet-teeth of each clutch-member being in slidible engagement with the ratchet-teeth of a respective crank-pedal, all arranged so that the reciprocatory motion of said crank-pedals will produce a continuous rotary motion 90 of said sprocket-wheel, combined with means connected and coöperating with said shaft to produce "back-pedaling," consisting of rearwardly extending rods fixed to said 95 shaft, a connecting bar between said rods, and foot-actuated means connected with said connecting bar, and means connected with said rearwardly extending rods for limiting 100 and arresting the downward movements of said crank-pedals, consisting of members extending downwardly from said rearwardly extending rods, and stop-pins extending laterally from said members with which said crank-pedals are adapted to be brought into 110 engagement.

In testimony that I claim the invention set forth above I have hereunto set my hand this 30th day of July, 1918.

CHARLES M. TATOSIAN.
